2 Claims. (Cl. 200—51)

The invention relates to a socket-switch combination for battery and, alternatively, automobile cigarette lighter operation of a dry shaver. The switch parts of the combined socket and switch turns the shaver on and off regardless of whether the shaver motor is powered by battery or via a cord inserted in the socket. A plug-switch of the general type is known from German Patent No. 123,043 dated November 1, 1927.

The principle object of the invention is to provide such a device which requires a minimum of space and can be inexpensively manufactured.

According to the invention this is achieved in that the socket is of the coaxial plug type having an outer contact tube concentric within a substantially disc-shaped, rotatably journaled switching member of insulating material. A toggle action spring is provided to hold the switch in its switched positions. A flat switching contact is provided on the switch disc at right angles to the axis of rotation and cooperates with fixed contact springs connected to the base plate of the socket-switch member.

In order that the invention may readily be carried into effect, it will now be described more fully, by way of example, with reference to the accompanying drawing which shows a presently preferred embodiment.

FIG. 1 is a plan view, partly in cross-section, of a socket-switch according to the invention.

FIG. 2 shows the device of FIG. 1 in a side-elevation view and partly in an axial cross-section.

FIG. 3 is an inverted plan view of the underside of the device seen in FIG. 1.

The device shown in the drawing is provided, preferably in the manner shown, on an insulating base plate 1, for example, consisting of hard paper, having an aperture which consists of a substantially circular part 3 and joining thereto a lateral aperture extension 5. The aperture 3, is for the greater part covered by an insulating carrier plate 7, for example, consisting of a synthetic resin (see FIGS. 2 and 3) which is connected to the base plate 1 by means of two flanged eyelets 9 and 11. Plate 7 does not cover aperture extension 5 however.

The carrier plate 7 supports a coaxial plug contact consisting of a central pin 13 and a contact tube 15 coaxially surrounding the pin 13. The central contact pin 13 is provided with a collar 17 and at the rear end (in FIG. 2 the top end) with a bent flange 19 which connects the pin to the base plate. Between the pin collar 17 and the base plate 7 are clamped successively, an insulating ring 21, the apertured bottom 23 of the contact tube 15 (in FIG. 2 the upper edge), and a metal connection strip 25, all on one side of the carrier plate 7. On the opposite side of plate 7 is a metal connection strip 27 and a soldering tag 29 also clamped to the base plate by the flange 19 of pin 13, shaped switching member 31, consisting of insulating material, for example synthetic resin, is rotatably journaled. On the side of the disc-shaped switching member 31, facing the base plate 1, is a flat contact 33 in a plane at right angles to the axis of rotation. Contact 33 co-operates with two strip-shaped contact springs 35 and 37 which are approximately in alignment. The ends of contacts 35 and 37

2

are remote from one another and are hooked into apertures 39 and 41 of the base plate 1 and are held in these apertures by tags 43 and 45 respectively projecting into the apertures 39 and 41.

5 As shown in FIG. 1 the coaxial plug contact consisting of pin 13, tube 15 and the tubular shaft 47 of the disc-shaped switching member 31 are at least partially within the circular part of the aperture 3. Shaft 47 of switching member 31 has a radial extension 49 (see FIG. 10) 1) in the form of a rib which is arranged in parallel with the shaft 47 and has an end projecting beyond shaft 47 in the direction of base plate 1 (in FIG. 1 directed backwards). The free end of projection 49 engages one 15 end of a toggle action spring 51 provided in the aperture extension 5. The other end of that spring is connected to a tag 53 projecting in to the opening 5. As a result of the action of this toggle action spring, the switching member 31, has two stable switched positions, one of which is shown in FIG. 1. An axial projection 20 55 (FIG. 2) of the switching member 31, serving as operating knob. As best shown in FIG. 1, the position of the contact member 31 is that in which the contact springs 35 and 37 are not connected together.

25 By comparing FIGS. 1 and 2 it will be seen that contact pin 13 is connected electrically to the soldering tag 29 as well as the strip 27 and via the flanged eyelet 9 to a contact strip 57 on the other side of base plate 1. The other end of strip 57 is connected in an aperture 59 of the base plate 1 in a manner similar to that of 30 the contact springs 35 and 37. The contact tube 15 of the coaxial plug contact is connected via the connection strip 25 and eyelet 11 to a similar connection strip 61 at one end. The other end of strip is fastened to plate 1 similar to the connection strip 57. Strip 61 also serves 35 as a soldering tag.

As appears from the above, by using a coaxial plug contact and using the outer contact tube 15 as the fixed shaft for the switching member 31, a device is obtained which consists of component parts which can easily be 40 manufactured by pressing and punching and assembled by a single clamp provided by pin 13. Also, owing to the use of a substantially disc-shaped switching member provided with a contact at right angles to the axis of rotation, very little space is required, in particular, 45 in an axial direction. A further decrease of the axial dimension is possible by providing, in the manner described, the toggle action spring and parts of the plug contact in the apertures 5 and 3 of the base plate 1.

Obviously a plug socket-switch combination is useful 50 with any battery powered device which may also operate from another source of energy via a plug-in conductor.

What is claimed is:

1. A plug socket-switch combination comprising a base 55 plate of insulating material, at least one aperture in said base plate, a carrier plate connected with said base plate at one side thereof and overlying said one aperture, a socket tube coaxially surrounding a socket pin and a disc shaped switch member concentrically surrounding said socket tube, said switch member being rotatably journaled on said socket tube, said socket pin having a radial collar intermediate its ends and located within said tube, said socket pin extending at one end through said carrier plate, a plurality of strip conductors associated with said socket pin and tube on each 60 side of said carrier plate, said socket pin having said one end flared over said carrier plate for clamping said socket tube and pin and their associated strip conductors and said switch member in operative relation on said carrier plate, means for biasing said switch member in its 65 switched positions and conductor means connected with said base member operatively connected with said switch member.

2. A plug socket-switch combination according to claim 1 wherein said base plate has a lateral aperture extension connected with said one aperture and said means for biasing said switch member comprises a toggle spring receivable in said lateral aperture, means connecting said toggle spring and switch member at one end of said spring, and means connecting the other end of said spring with said base plate.
